(57) CLAIM

The ornamental design for an air freshener container and lid, as shown and described.

DESCRIPTION

FIG. 1 is a right front perspective view of an air freshener container and lid;

FIG. 2 is a left bottom perspective view of the air freshener container and lid of FIG. 1;

FIG. 3 is a top plan view of the air freshener container and lid of FIG. 1;

FIG. 4 is a bottom plan view of the air freshener container and lid of FIG. 1;

FIG. 5 is right side elevational view of the air freshener container and lid of FIG. 1;

FIG. 6 is a left side elevational view of the air freshener container and lid of FIG. 1;

FIG. 7 is a front elevational view of the air freshener container and lid of FIG. 1;

FIG. 8 is a rear elevational view of the air freshener container and lid of FIG. 1;

FIG. 9 is a right front perspective view of an air freshener lid;

FIG. 10 is a left bottom perspective view of the air freshener lid of FIG. 9;

FIG. 11 is a top plan view of the air freshener lid of FIG. 9;

FIG. 12 is a bottom plan view of the air freshener lid of FIG. 9;

FIG. 13 is a right side elevational view of the air freshener lid of FIG. 9;

FIG. 14 is a left side elevational view of the air freshener lid of FIG. 9;

FIG. 15 is a front elevational view of the air freshener lid of FIG. 9; and,

FIG. 16 is a rear elevational view of the air freshener lid of FIG. 9.

The broken lines showing portions of the air freshener container and lid are included for the purpose of illustrating the portions of the article and form no part of the claimed design.

1 Claim, 8 Drawing Sheets
